FOUR WHEEL TRACTOR

Erval D. Jackson, R.R. 2, Edgely, N. Dak.

Filed Apr. 13, 1970, Ser. No. 22,386

Term of patent 14 years

Int. Cl. D12—09

U.S. Cl. D14—3

FIG. 1 is a perspective view of a four wheel tractor embodying my design.

FIG. 2 is a side elevational view thereof.

FIG. 3 is a top plan view of my tractor design.

FIG. 4 is a cross-sectional view taken along line 4-4 of FIG. 3.

The characteristics features of my design reside in the combination of oil tanks attached to the rear of the front fenders on either side of the tractor, and in the tanks having steps attached thereto and extending rearward therefrom, and in the oil tanks being tapered to blend with the shape of the front fenders of the tractor, and in the tool box being mounted on the front of the rear fender of the tractor.

I claim:

The ornamental design for a four-wheel tractor, as shown and described.
